ARTICLE OPERATED SWITCH

Paul A. Nelson, Minneapolis, Minn.

Application March 10, 1948, Serial No. 14,015

2 Claims. (Cl. 200—52)

1

This invention has relation to an article retaining device adapted to be especially useful as an adjunct to an ordinary telephone.

An object of the invention is to provide a new and improved device, for use at the location of a telephone, equipped to contain articles, such as writing implements and paper, frequently employed when telephoning, in conveniently accessible position.

A further object is to provide an article retaining device of the character as stated, which will incorporate a novel and improved construction and arrangement for removably supporting a writing implement, such as a pencil, in said device in such manner as to make it improbable that the writing implement after a use thereof will not be replaced in the device unless this is intentional.

A further object is to provide in the device, a new and improved mechanism for removably supporting a writing implement, such as a pencil, adapted to be actuated upon withdrawal of the writing implement to cause an electric circuit including a visible lamp of said device to be made and upon insertion of said writing implement to cause said electric circuit to be broken.

And a further object is to provide an article retaining device wherein will be incorporated desirable and improved features and characteristics of construction novel both as individual entities of the device and in combination with each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawing forming a part of this specification,

Fig. 1 is a perspective view of an article retaining device made according to the invention;

Fig. 2 is an enlarged horizontal sectional view of the article retaining device, taken as on line 2—2 in Fig. 3;

Fig. 3 is a vertical sectional view, taken as on line 3—3 in Fig. 2;

Fig. 4 is a detail sectional view corresponding generally with the disclosure at the left upper corner of Fig. 3; and

Fig. 5 is a wiring diagram.

2

A base housing member of the article retaining device is constituted as a horizontal rectilinear member 10 providing a horizontal rectilinear compartment 11 open at the lower front of said device, and a body housing member is constituted as a vertical rectilinear member 12 providing forward and rearward vertical rectilinear compartments, denoted 13 and 14, respectively, of the device. The compartment 13 is comparatively smaller than the compartment 14, and a horizontal dividing wall 15, between and constituted as a part of both the base and body housing members, bounds the upper side of the horizontal compartment 11 and the lower ends of the vertical compartments 13 and 14. A vertical partition wall 16, between the rear of the vertical compartment 13 and the front of the vertical compartment 14, spans the distance between the side walls of the body housing member, and portions of the base housing member extend to positions beyond said body housing member side walls in the disclosure as made. A rear wall 17 of the body housing member, at the rear of the vertical compartment 14, is removable, and a front wall 18 of said body housing member, at the front of the vertical compartment 13, will be of transparent or translucent material, glass as shown.

Mechanism of the article retaining device for removably supporting a writing implement, such as a pencil, is situated in an upper portion of the forward vertical compartment 13. Spaced apart, horizontal supporting rods, indicated 19, 19, for said mechanism are situated in spaced, adjacent relation to an upper wall 20 of the body housing member 12 and extend from front to rear of the compartment 13. Rearward end portions of the rods 19, 19 are fixedly supported, as at 21, on the partition wall 16, and forward end portions of said rods are fixedly supported, as at 22, on the front wall 18.

Oppositely disposed, horizontal, substantially parallel insulating strips or blocks, represented 23, 23, are situated in the compartment 13 to extend at right angular relation to the supporting rods 19, 19, and said insulating strips or blocks are slidably mounted on said supporting rods. More explicitly stated, the insulating strips or blocks include transverse openings through which the supporting rods pass more or less freely, and the construction and arrangement will be such that said supporting rods will retain said insulating strips or blocks in substantially parallel relation while they are slid relative to each other in a manner to be made plain. Compression coil springs 24, four as shown, upon the supporting

rods 19, 19 and between the insulating strips or blocks and the partition wall 16 and the front wall 18, respectively, exert resilient action urging said insulating strips or blocks toward each other.

An opening 25 through the upper wall 20 of the body housing member 12 is in vertical alinement with midlength portions of the insulating strips or blocks 23, 23 which are adjacent each other, and interior sides of said midlength portions are cut away, as at 26, to provide an opening between said insulating strips or blocks in vertical alinement with the opening 25. The construction and arrangement desirably can be such that the cut-away portions 26 provide an opening which would be circular in the event the insulating strips or blocks 23, 23 became interengaged.

The opening 25 and the opening provided by the cut-away portions 26 are adapted to receive a writing implement, such as a pencil, adapted to be thrust vertically through said openings. Said opening 25 will be sufficiently large to freely receive said writing implement. Said opening provided by cutting away the insulating strips or blocks will be of diameter greater than that of the advance end of the writing implement and less than that of the body of said writing implement when said insulating strips or blocks are closely adjacent each other. Or, the upper parts of the cut-away portions 26 can be made to flare outwardly to freely receive the advance end of a writing implement and guide it into lower parts of said cut-away portions defining an opening of diameter smaller than the writing implement when the insulating blocks or strips are close together. The construction and arrangement will be such that a writing implement, such as a pencil, of appropriate size when thrust into the vertically alined openings will cause the insulating strips or blocks 23, 23 to be forcibly moved apart against resilient action of the compression coil springs 24 and also such that said compression coil springs will exert resilient action upon the writing implement to cause it to be removably retained by and between said insulating strips or blocks. The pressure exerted upon the writing implement desirably will be slight so that said writing implement can be readily and easily withdrawn from the device when this is intentional, and, of course, the compression coil springs will cause the insulating strips or blocks to be moved toward each other upon withdrawal of said writing implement.

Each of the insulating strips or blocks 23 supports a pair of spaced apart, movable contact elements. As disclosed, the pair of movable contact elements which each insulating strip or block supports are at the opposite ends of the insulating strip or block, and movable contact elements on the different insulating strips or blocks at the same side of the compartment 13 are in alined relation in direction longitudinally of the supporting rods 19, 19. That is, there are alined movable contact elements, designated 27 and 28, supported by the different insulating strips or blocks at one side of the compartment 13 and alined movable contact elements, indicated 29 and 30, supported by said different insulating strips or blocks at the opposite side of said compartment 13 adapted, respectively, to become disengaged in response to insertion of a writing implement into the device and engaged in response to withdrawal of the writing implement.

An electric lamp suitably and conveniently supported in a lower portion of the compartment 13, upon the dividing wall 15 and adjacent the front wall 18, is denoted 31, and a battery suitably and conveniently stably situated in the compartment 14 is represented 32.

5 A lead wire 33 extends from the battery 32 to the lamp 31, a lead wire 34 extends from said lamp to the movable contact element 29, a connecting wire between said movable contact element 29 and the movable contact element 27 is indicated 35, a connecting wire between the movable contact element 30 and the movable contact element 28 is represented 36, and a lead wire 37 extends from said movable contact element 28 to said battery.

15 A removable drawer 38, for paper, etc., is situated in the horizontal compartment 11.

In Fig. 1 of the drawing, a writing implement, disclosed as a pencil A, is inserted in the device and the lamp 31 is extinguished. Upon withdrawal of the pencil, said lamp 31 will become lighted and remain lighted until the pencil is replaced. Light from the lamp, visible at the front of the transparent or translucent front wall 18, will be much more apt to call attention to the fact that a withdrawn pencil has not been replaced than would the pencil itself alone, especially when the lamp is lighted in a space otherwise dark. Stated differently, the lighted lamp will make it improbable that a user of the pencil will neglect to replace it. Of course, light furnished by the lamp can be employed to useful purposes, such, for example, as illuminating the dial of a telephone, pages of a directory, paper upon which a user may desire to write, etc.

20 Although the battery 32 is an especially convenient source of supply for accomplishing energization of the lamp 31, it is to be understood that the circuit including said lamp could be supplied with electrical energy from a source in remote relation to the article retaining device.

25 Paper, etc., in the removable drawer 38 is conveniently accessible at a location in front of a lower portion of the device which evidently will be illuminated when the lamp 31 is lighted.

30 What is claimed is:

1. In a device of the character described, a switch for removably supporting a switch operator including spaced apart, parallel supporting rods, a pair of parallel insulating blocks mounted upon said parallel rods in perpendicular relation thereto for relative rocking movement and movement toward and away from each other, contact elements supported by said insulating blocks, respectively, including a set of contact elements disposed at the outer side of each of said parallel rods, the contact elements of either of which sets can be engaged to cause a circuit to be made and the contact elements of both of which sets are required to be disengaged to cause the circuit to be broken and resilient means actuatable upon withdrawal of the switch operator from said switch to cause said insulating blocks to be moved toward each other and contact elements of each of said sets to become engaged, said insulating blocks being adapted to be forcibly moved apart in response to insertion of said switch operator into a portion of the switch between both the parallel rods and insulating blocks to cause said contact elements of both sets to become disengaged.

2. In a device of the character described, a switch for removably supporting a switch operator including spaced apart, parallel supporting rods, a pair of insulating blocks mounted upon said insulating rods in perpendicular relation

thereto for relative rocking movement and movement toward and away from each other, contact elements supported by said insulating blocks, respectively, including a set of contact elements disposed at the outer side of each of said parallel rods, the contact elements of either of which sets can be engaged to cause a circuit to be made and the contact elements of both of which sets are required to be disengaged to cause said circuit to be broken, a conductor between the contact elements upon each of said insulating blocks and resilient means upon said parallel rods engaged against base portions of exterior surfaces of the insulating blocks actuatable upon withdrawal of the switch operator from said switch to cause said insulating blocks to move toward each other and the contact elements of each of said sets to become engaged, said insulating blocks being adapted to be forcibly moved apart in response to insertion of said switch operator into a portion of the switch between both the parallel rods and insulating blocks to cause the contact elements of both of said sets to become disengaged.
